CLAIM

The ornamental design for a stethoscope with one-piece tubing, chest piece and diaphragm-rim, as shown and described.

DESCRIPTION

FIG. 1 is a perspective view of a stethoscope with one-piece tubing, chest piece and diaphragm-rim;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the stethoscope with one-piece tubing, chest piece and diaphragm-rim in FIGS. 1-7 shown in broken lines are included to show features that form no part of the claimed design.
